Primary Examiner — Christine J Skubinna(74) *Attorney, Agent, or Firm* — Husch Blackwell LLP(57) **ABSTRACT**

A fixture carrier for supporting a plumbing fixture includes an upright and an arm. The arm is coupled to the upright and is configured to support the plumbing fixture. The arm includes a base, and an extension configured to move relative to the base. The arm is configurable in a first position where at least a portion of the base is retracted into the extension, a second position where the extension is extended away from the base, and a plurality of positions between the first position and the second position.

FIG. 2

FIG. 3

FIG. 4

MODULAR ARM FOR FIXTURE CARRIER**CROSS-REFERENCE TO RELATED APPLICATIONS**

This application is a non-provisional of and claims benefit of U.S. Provisional Patent Application No. 63/003,796, filed on Apr. 1, 2020, the entire contents of which are incorporated herein by reference.

FIELD OF THE INVENTION

The present disclosure relates to a fixture carrier for supporting a plumbing fixture, and more specifically, to a fixture carrier including a modular arm.

BACKGROUND

Fixture carriers are used to support plumbing fixtures, such as service sinks, lavatories, urinals, water coolers, etc. during installation. Fixture carriers typically include a stationary arm configured to support plumbing fixtures of a specific shape and size. As such, when installing fixtures of different sizes, a user may need to use various different fixture carriers, which include different arms having different size capacities.

SUMMARY

In one aspect, the invention provides a fixture carrier for supporting a plumbing fixture, including an upright, and an arm coupled to the upright and configured to support the plumbing fixture, the arm including a base, and an extension configured to move relative to the base, wherein the arm is configurable in a first position where at least a portion of the base is retracted into the extension, a second position where the extension is extended away from the base, and a plurality of positions between the first position and the second position.

In another aspect, the invention provides a fixture carrier for supporting a plumbing fixture, including an upright, and an arm coupled to the upright and configured to support the plumbing fixture, the arm including a first portion coupled to the upright, and a second portion coupled to the first portion and including a bore, wherein the first portion is configured to be threadably received within the bore.

In another aspect, the invention provides a fixture carrier for supporting a plumbing fixture, including an upright defining a first axis, a cross-bar coupled to the upright and defining a second axis oriented perpendicular to the first axis, a coupling mechanism coupled to the upright, and an arm configured to support the plumbing fixture and defining a third axis oriented perpendicular to the first axis and the second axis, wherein the arm includes a first portion removably coupled to the coupling mechanism, and a second portion removably coupled to the first portion, wherein the second portion is configured to move about the third axis relative to the first portion.

Other aspects of the disclosure will become apparent by consideration of the detailed description and accompanying drawings.

BRIEF DESCRIPTION OF THE DRAWINGS

FIG. 1 is a front perspective view of a fixture carrier for supporting a plumbing fixture embodying the invention.

FIG. 2 is a rear perspective view of the fixture carrier of FIG. 1.

FIG. 3 is a front view of the fixture carrier of FIG. 1.

FIG. 4 is a side view of the fixture carrier of FIG. 1.

5 FIG. 5A is a perspective view of an arm of the fixture carrier of FIG. 1.

FIG. 5B is a side view of the arm of FIG. 5A.

FIG. 6A is a perspective view of an alternative arm for use with the fixture carrier of FIG. 1 in a retracted position.

10 FIG. 6B is a perspective view of the arm of FIG. 6A in an extended position.

FIG. 7A is a perspective view of an alternative arm for use with the fixture carrier of FIG. 1 in a retracted position.

15 FIG. 7B is a perspective view of the arm of FIG. 7A in an extended position.

FIG. 8A is a perspective view of an alternative arm for use with the fixture carrier of FIG. 1 in a retracted position.

FIG. 8B is a perspective view of the arm of FIG. 8A in an extended position.

20 FIG. 9A is a perspective view of an alternative arm for use with the fixture carrier of FIG. 1 in a retracted position.

FIG. 9B is a perspective view of the arm of FIG. 9A in an extended position.

FIG. 10A is a perspective view of an alternative arm for use with the fixture carrier of FIG. 1 in a retracted position.

25 FIG. 10B is a perspective view of the arm of FIG. 10A in an extended position.

FIG. 11A is a perspective view of an alternative arm for use with the fixture carrier of FIG. 1 in a retracted position.

30 FIG. 11B is a perspective view of the arm of FIG. 11A in an extended position.

FIG. 12A is a perspective view of an alternative arm for use with the fixture carrier of FIG. 1 in a retracted position.

FIG. 12B is a perspective view of the arm of FIG. 12A in an extended position.

FIG. 13A is a perspective view of an alternative arm for use with the fixture carrier of FIG. 1 in a retracted position.

FIG. 13B is a perspective view of the arm of FIG. 13A in an extended position.

40 FIG. 14A is a perspective view of an alternative arm for use with the fixture carrier of FIG. 1 in a retracted position.

FIG. 14B is a perspective view of the arm of FIG. 14A in an extended position.

FIG. 15A is a perspective view of an alternative arm for use with the fixture carrier of FIG. 1 in a retracted position.

45 FIG. 15B is a perspective view of the arm of FIG. 15A in an extended position.

FIG. 16A is a perspective view of an alternative arm for use with the fixture carrier of FIG. 1 in a retracted position.

50 FIG. 16B is a perspective view of the arm of FIG. 16A in an extended position.

FIG. 17A is a perspective view of an alternative arm for use with the fixture carrier of FIG. 1 in a retracted position.

FIG. 17B is a perspective view of the arm of FIG. 17A in an extended position.

FIG. 18A is a perspective view of an alternative arm for use with the fixture carrier of FIG. 1 in a retracted position.

55 FIG. 18B is a perspective view of the arm of FIG. 18A in an extended position.

FIG. 19A is a perspective view of an alternative arm for use with the fixture carrier of FIG. 1 in a retracted position.

FIG. 19B is a perspective view of the arm of FIG. 19A in an extended position.

60 FIG. 20A is a perspective view of an alternative arm for use with the fixture carrier of FIG. 1 in a retracted position.

65 FIG. 20B is a perspective view of the arm of FIG. 20A in an extended position.

FIG. 21A is a perspective view of an alternative arm for use with the fixture carrier of FIG. 1 in a retracted position.

FIG. 21B is a perspective view of the arm of FIG. 21A in an extended position.

FIG. 22A is a perspective view of an alternative arm for use with the fixture carrier of FIG. 1 in a retracted position.

FIG. 22B is a perspective view of the arm of FIG. 22A in an extended position.

DETAILED DESCRIPTION

Before any embodiments of the disclosure are explained in detail, it is to be understood that the disclosure is not limited in its application to the details of the formation and arrangement of components set forth in the following description or illustrated in the accompanying drawings. The disclosure is capable of supporting other implementations and of being practiced or of being carried out in various ways.

The figures and accompanying description provide adjustable fixture carriers that are configured to accommodate various sized plumbing fixtures, such as service sinks, lavatories, urinals, water coolers, etc. The adjustable fixture carriers also incorporate simplified structures to provide labor and installation cost savings.

FIGS. 1-4 illustrate a fixture carrier 10 according to an embodiment of the present disclosure. The fixture carrier 10 includes a frame 14, which is adjustable in order to accommodate plumbing fixtures of various sizes. Specifically, the frame 14 is adjustable in a horizontal direction and a vertical direction. The horizontal direction is a direction extending along an X-axis 18, and the vertical direction is a direction extending along a Y-axis 22. The frame 14 is also adjustable in a direction extending along a Z-axis 26.

With reference to FIGS. 1-4, the frame 14 includes a first upright 30, a second upright 34 horizontally spaced a distance from the first upright 30, a first, or upper, cross-bar 38, and a second, or lower, cross-bar 42. The first cross-bar 38 is secured to the first upright 30 and the second upright 34. Similarly, the second cross-bar 42 is secured to the first upright 30 and the second upright 34. The frame 14 additionally includes a first arm 46 and a second arm 50 configured to support the fixture being installed. The first arm 46 is adjustably coupled to the first upright 30 with a first coupling mechanism 54. The first coupling mechanism 54 includes a first bracket 58 and a first plate 66. The second arm 50 is adjustably coupled to the second upright 34 with a second coupling mechanism 56. The second coupling mechanism 56 includes a second bracket 62 and a second plate 70.

The first upright 30 and the second upright 34 are substantially identical, elongate beams. The first upright 30 includes a first end 33 and an opposite second end 35. The second upright 34 includes a first end 29 and an opposite second end 31. Each of the uprights 30, 34 additionally include a foot 90 positioned on the second end 31, 35 of each of the uprights 30, 34. The feet 90 are substantially rectangular plates configured to engage a work surface and support the fixture carrier 10 during use.

Each of the cross-bars 38, 42 are rectangular and planar. The first cross-bar 38 extends between and is coupled to the first and second uprights 30, 34. The first cross-bar 38 includes a first end 37 coupled to the first upright 30 and a second end 39 coupled to the second upright 34. The second cross-bar 42 also extends between and is coupled to the first and second uprights 30, 34. The second cross-bar 42 includes a first end 41 coupled to the first upright 30 and a

second end 43 coupled to the second upright 34. The first cross-bar 38 is coupled to the uprights 30, 34 closer to the first ends 29, 33 of the uprights 30, 34, and the second cross-bar 42 is coupled to the uprights 30, 34 closer to the second ends 31, 35 of the uprights 30, 34.

The first and second brackets 58, 62 are removably coupled to the uprights 30, 34 and vertically moveable to a position between the first end 29, 33 of the uprights 30, 34 and the first cross-bar 38. Specifically, the first bracket 58 is coupled to the first upright 30 and the second bracket 62 is coupled to the second upright 34. Each of the brackets 58, 62 are U-shaped and include studs # for securing the brackets 58, 62 to the plates 66, 70. When positioning the bracket 58, 62 on the upright 30, 34, the user may slide the bracket 58, 62 along the longitudinal axis 74 to a desired position. Then, the user may insert a fastener into the brackets 58, 62, thereby securing the brackets 58, 62 against the uprights 30, 34 and preventing movement of the brackets 58, 62 in either a horizontal or vertical direction.

With continued reference to FIGS. 1-4, the first plate 66 is positioned between the first bracket 58 and the first arm 46. The second plate 70 is positioned between the second bracket 62 and the second arm 50. The plates 66, 70 are rectangular in shape. The plates 66, 70 include a first elongated slot 142 and a second elongated slot 146 extending through the thickness of the plate. The first slot 142 is positioned near the top edge 126 of the plate. The first slot 142 is parallel to the top and bottom edges 126, 130. Similarly, the second slot 146 is positioned near the bottom edge 130 of the plate. The second slot 146 is parallel to the top and bottom edges 126, 130 and to the first slot 142. The first and second slots 142, 146 are shaped and sized to receive the studs 118 of the bracket 58, 62. During installation of the plates 66, 70 onto the brackets 58, 62, a user may position the plates 66, 70 against the brackets 58, 62, thereby allowing the studs 118 to protrude through the first and second slots 142, 146. In order to move the plates 66, 70 to the desired position, the user may slide the plates 66, 70 in the horizontal direction. As the plates 66, 70 slide, the studs 118 slide along the first and second slots 142, 146. The user may secure the position of the plates 66, 70 relative to the brackets 58, 62 by securing a fastener to the studs 118. With continued reference to FIGS. 1-4, each plate 66, 70 includes a receptacle 150 extending from a front face of the plates 66, 70. As illustrated, the receptacle has a circular cross-section, however other cross-sections may also be implemented. The plates 66, 70 are independently movable relative to each other. The receptacles 150 additionally include an inner surface having threads. Specifically, each of the receptacles 150 are sized to receive and secure the arms 46, 50 to the plates 66, 70. During installation of the fixture carrier 10, the arms 46, 50 may be secured to the receptacles 150 such that the arms 46, 50 are axially movable with the plates 66, 70 in the horizontal direction.

The arms 46, 50 extend from the frame 14 to support a plumbing fixture during use. With reference to FIG. 5A-5B, the first and second arms 46, 50 include a body 162 and elongated slots 166 extending into the body 162. The body 162 is cylindrical in cross-section and includes a first end 45, 49, and a second end 47, 51 opposite the first ends 45, 49. The first ends 45, 49 of the arms 46, 50 extend outward from the frame 14 and the second ends 47, 51 of the arms 46, 50 are secured to the receptacles 150 of the plates 66, 70. The second ends 47, 51 of the arms 46, 50 include threads 164 corresponding to the threads positioned on the inner surfaces 158 of the receptacles 150. Therefore, each of the arms 46, 50 are threadably coupled to the receptacles 150. In alternative

embodiments, the arms 46, 50 may be threaded along the length or partial length of the body 162. In alternative embodiments, the arm 46, 50 may be secured to the receptacle 150 via several fasteners (e.g., threaded fasteners). Specifically, the receptacle 150 includes various threaded apertures equidistantly spaced around the perimeter of the receptacle 150. After the arm 46, 50 is positioned within the receptacle 150, the fasteners are threaded into the apertures and into abutment with the arm 46, 50. The fasteners may be continually threaded until there is a snug connection between the fasteners and the arm 46, 50, thereby inhibiting the arm 46, 50 from moving.

In the illustrated embodiments, the slots 166 are elongate apertures, which extend through the arm 46, 50. In some embodiments, the slots 166 may extend along the length of the body 162 or include alternative shapes and sizes. In such instances, the body 162 may include one or several slots 166. In some constructions, the slot(s) 166 are recessed within the body 162 and do not extend completely through the body 162.

The arms further include sleeves 174 (FIGS. 1-2 and 4) supported by the arms 46, 50 and movable (e.g., slideable) along the arms 46, 50 in a direction parallel to the Z-axis 26. In some embodiments, the sleeves 174 may also or alternatively rotate relative to the arms 46, 50. Each of the sleeves 174 include a body having an outer surface configured to be engaged by the user to move the sleeve relative to the arms 46, 50. In the illustrated embodiments, each of the sleeves 174 are secured to the arms via pins or set screws. Each of the sleeves 174 includes an aperture extending through the sleeve 174. The sleeve apertures and the slots of the body are shaped and sized to receive the pin or set screw. The pin extends through the sleeve aperture and the slot to secure the sleeve in a specific position on the arms 46, 50.

The pins are slideable along the length of the slot 166, such that movement of the pin axially repositions the sleeve relative to the body 162. Specifically, a user may slide the pin to a position such that it aligns with a corresponding aperture on a plumbing fixture. A user may secure the pin and the sleeve in a desired position via a fastener (e.g., a screw and/or a lock down). The pin may then protrude through the corresponding aperture on the plumbing fixture and support the fixture during use. As such, the sleeves and pins may be repositioned in a direction parallel to the Z-axis 26 to align with plumbing fixtures of various lengths. In some embodiments, the pins may be placed directly within the slots 166, without the use of the sleeves.

In alternative embodiments, the pin may be a cotter pin, or alternative type of fastener. In still further embodiments, the pin may be a bolt. In such instances, the bolt may be tightened to secure the arm 46, 50 to the sleeve and/or to secure the arm 46, 50 to the receptacle 150. In still further embodiments, the pin may be a spring-loaded actuator. In such instances, the actuator is positioned within the slot 166 on the arm 46, 50. A spring biases the actuator upwards through the slot 166 and the sleeve aperture, thereby preventing movement of the sleeve relative to the arm 46, 50.

With continued reference to FIGS. 5A-5B, the first and second arms 46, 50 additionally include notches 178 extending at least partially around a circumference of the body 162. The notches 178 are recessed grooves extending into the body 162 of the arm 46, 50 and form “cut-off” points in the arms 46, 50. In other words, in the event that the user requires a shorter arm, the user may break the arm 46, 50 at one of the notches 178, thereby creating a shorter arm. In the illustrated embodiments, the arms 46, 50 include two

notches 178. However, in alternative embodiments, the arms may include fewer or more notches.

The fixture carrier 10 is used to support a plumbing fixture being installed in a structure. The fixture carrier 10 may be adjusted to support different fixtures of various sizes. The position of the sleeves 170 may be adjusted relative to the arms 46, 50 in order to accommodate fixtures of various depths. Specifically, the user may slide each of the sleeves 170 along the arm 46, 50 and align the sleeve aperture with the slots 166 of the body 162. The user may then insert the pin through the aperture and the slot 166 and secure the positioning of the pin by inserting a fastener. The plumbing fixture may be placed on the frame 14 for support.

FIGS. 6A-22B illustrate alternative arms for use with the fixture carrier 10. The illustrated arms are similar to the arms 46, 50 described above and include like parts. Reference is hereby made to the description of the fixture carrier 10 and arms 46, 50 shown in FIGS. 1-5B for description of features and elements of the arms not included below.

FIGS. 6A-7B illustrate another embodiment of an arm 46a, with like components designated with an “a.” The arm 46a is largely identical to the arms 46, 50, with some differences, as described below.

With reference to FIGS. 6A-6B, the arm 46a is cylindrical in cross-section. The arm 46a additionally includes a stationary base 182a and an extension 186a, which is movable relative to the base 182a. The base 182a includes a first end 181a, and a second end 183a opposite the first end 181a. The first end 181a extends outward from the frame 14, and the second end 183a of the arm 46a is secured to the receptacle 150 of the plate 66, 70. The second end 183a includes a connection portion 190a having threads 194a corresponding to the threads positioned on the inner surface of the receptacle 150. Therefore, the connection portion 190a of the arm 46a is threadably coupled to the receptacle 150. In alternative embodiments, the base 182a may be threaded along the length or partial length of the base 182a. In alternative embodiments, the arm 46a may be secured to the receptacle 150 via fasteners.

The base 182a additionally includes a first channel 198a and a second channel 202a extending from the first end 181a of the base 182a to a first end 189a of the connection portion 190a. The first channel 198a and the second channel 202a are U-shaped, and the first channel 198a is positioned on an opposite side of the base 182a as the second channel 202a. The base 182a includes elongate slots 166a extending through the base 182a. The slots 166a are elongate apertures, which extend along substantially the entire non-threaded portion of the base 182a. However, in alternative embodiments, the slots 166a may extend along a shorter or longer portion of the base 182a. In some constructions, the slot(s) 166a are recessed within the base 182a and do not extend completely through the base 182a. In the illustrated embodiments, the base 182a includes two slots 166a. However, in alternative embodiments, the base 182a may include fewer or more slots.

The extension 186a includes a first end 185a, and a second end 187a opposite the first end 185a. The extension 186a is cylindrical and includes a cut-out 206a extending from the second end 187a of the extension 186a through a portion of the extension 186a. The cut-out 206a forms a solid portion 210a, a first elongate arm 214a, and a second elongate arm 218a. The elongate arms 214a, 218a extend from the solid portion 210a. The solid portion 210a includes an elongate slot 218a, or aperture, extending through the extension 186a. In the illustrated embodiments the solid portion 210a includes one slot 222a. However, in alternative

embodiments, the solid portion 210a may include fewer or more slots. The arms 214a, 218a extend from the solid portion 210a and are oriented parallel to each other and on opposite sides of the extension 186a. The arms 214a, 218a are shaped and sized to be received within the first channel 198a and the second channel 202a of the base 182a. The arms 214a, 218a include elongate slots 226a, or apertures, extending through the extension 186a. In the illustrated embodiments, the arms 214a, 218a include two elongate slots 226a. However, in alternative embodiments, the arms 214a, 218a may include fewer or more slots.

The arm 46a may additionally or alternatively include a sleeve, or collar, (not shown) supported by the arm 46a movable (e.g., slidably) along the arm 46a. The sleeve includes an outer surface engageable by the user to move the sleeve relative to the arm 46a. Specifically, the sleeve may be two washers secured together via a fastener (e.g., a bolt, etc.). The sleeve clamps around the arm 46a in order to secure the extension 186a to the base 182a in a given position. In some embodiments, the sleeve includes apertures extending through the sleeve. The apertures, the slots 166a on the base 182a, and the slots 222a, 226a on the extension 186a are shaped and sized to fasteners (e.g., pins).

In order to position the arm 46a during operation, the user secures the arm 46a to the plumbing fixture by threading the connection portion 190a of the base 182a into the receptacle 150. The user then positions the extension 186a relative to the base 182a. Specifically, the user slides the extension 186a along the base 182a, causing the arms 214a, 218a to slide along the first and second channels 198a, 202a of the base 182a. The extension 186a may be coupled to the base 182a in a retracted position (FIG. 6A), in which the first end 181a of the base 182a abuts an end 212a of the solid portion 210a, a fully extended position, in which the first end 181a of the base 182a is positioned adjacent the second end 187a of the extension 186a, or a plurality of partially extended positions (FIG. 6B) between the retracted position and the fully extended position. In order to couple the extension 186a to the base 182a in a given position, the user secures the clamp around the extension 186a and the base 182a. In the retracted position, the slots 166a on the base 182a are aligned with the slots 226a of the arms 214a, 218a. The user positions fasteners (e.g., pins) through the slots 166a, 222a, 226a. The fasteners protrude through corresponding apertures on the plumbing fixture during use, securing the arm 46a to the plumbing fixture.

In some embodiments (FIGS. 7A-7B), the extension 186a may include projections 230a positioned on the end 212a of the solid portion 210a of the extension 186a, between the arms 214a, 218a, to provide an additional or alternative means of securing the extension 186a to the base 182a. Specifically, the extension 186a includes two projections 230a, such that the projections 230a are oriented parallel to each other and on opposite sides of the end 212a of the solid portion 210a of the extension 186a. The projections 230a include a cylindrical aperture 234a sized to receive a fastener. In some embodiments, the apertures 234a may include alternative shapes.

In the illustrated embodiments, as shown in FIGS. 7A-7B, the base 182a additionally includes grooves 238a positioned on the first end 181a of the base 182a, between the channels 198a, 202a. Specifically, the base 182a includes two grooves 238a, such that the grooves 238a are oriented parallel to each other and on opposite sides of the first end 181a of the base 182a. The grooves 238a are shaped and sized to receive the projections 230a. The grooves 238a include a cylindrical aperture 242a sized to receive a fastener. Specifically, the

apertures 242a have a shape and size corresponding to the cylindrical apertures 234a positioned on the projections 230a.

When the extension 186a is coupled to the base 182a in the retracted position (FIG. 7A), the projections 230a of the extension 186a engage the grooves 238a of the base 182a, aligning the apertures 234a on the projections 230a with the apertures 242a on the grooves 238a. The user may then insert fasteners through the apertures 234a, 242a, thereby securing the extension 186a to the base 182a.

FIGS. 8A-11B illustrate another embodiment of an arm 46b, with like components designated with a "b." The arm 46b is largely identical to the arms 46, 50, with some differences, as described below.

With reference to FIGS. 8A-8B, the arm 46b is cylindrical in cross-section. The arm 46b includes a stationary base 182b and an extension 186b, which is movable relative to the base 182b. The base 182b includes a first end 181b, and a second end 183b opposite the first end 181b. The first end 181b extends outward from the frame 14 and the second end 183b of the arm 46b is secured to the receptacle 150 of the plate 66, 70. The second end 183b of the base 182b includes a connection portion 190b having threads 194b corresponding to the threads positioned on the inner surface of the receptacle 150. Therefore, the connection portion 190b of the arm 46b is threadably coupled to the receptacle 150. In alternative embodiments, the arm 46b may be threaded along the length of partial length of the base 182b. In alternative embodiments, the arm 46b may be secured to the receptacle 150 via fasteners.

The first end 181b of the base 182b includes a rectangular key 246b, or keyed portion. The key 246b is recessed, such that a circumference of the key 246b is less than a circumference of the base 182b. The base 182b includes elongated slots 166b, or apertures, extending through the base 182b. In the illustrated embodiments, the base 182b includes one slot 166b extending along the key 246b, and two elongate slots 250b extending between the key 246b and the connection portion 190b of the arm 46b. In alternative embodiments, the slots 166b, 250b may include additional shapes or sizes, and/or extend along a shorter or longer portion of the base 182b. In some constructions, the slot(s) 166b, 250b are recessed within the key 246b and/or the arm 46b and do not extend completely through the key 246b and/or arm 46b. Additionally, in alternative embodiments, the base 182b may include fewer or more slots.

The extension 186b includes a first end 185b, and a second end 187b opposite the first end 185b. The extension 186b is cylindrical and includes a cut-out 206b extending from the second end 187b of the extension 186b through a portion of the extension 186b. The cut-out 206b forms a solid portion 210b, a first elongate arm 214b, and a second elongate arm 218b. The elongate arms 214b, 218b extend from the solid portion 210b. The solid portion 210b includes an elongate slot 222b, or aperture, extending through the extension 186b. In the illustrated embodiments, the solid portion 210b includes one slot 222b. However, in alternative embodiments, the solid portion 210b may include fewer or more slots. The arms 214b, 218b extend from the solid portion 210b and are oriented parallel to each other and on opposite sides of the extension 186b. More specifically, the arms 214b, 218b extend from an upper and lower surface of the solid portion 210b. The arms 214b, 218b are shaped and sized to receive the key 246b of the base 182b. The arms 214b, 218b include elongate slots 226b, or apertures, extending through the extension 186b. In the illustrated embodiments, the arms 214b, 218b include one elongate slot

226b. However, in alternative embodiments, the arms 214b, 218b may include additional slots.

The arm 46b additionally or alternatively includes a sleeve, or collar, (not shown) supported by the arm 46b movable (e.g., slidably) along the arm 46b. The sleeve includes an outer surface configured to be engaged by the user to move the sleeve relative to the arm 46b. Specifically, the sleeve may be two washers secured together via a fastener (e.g., a bolt, etc.). The sleeve clamps around the arm 46b in order to secure the extension 186b to the base 182b in a given position. In some embodiments, the sleeve includes apertures extending through the sleeve. The apertures, the slots on the base, and the slots on the extension are shaped and sized to fasteners (e.g., pins).

In order to position the arm 46b during operation, the user secures the arm 46b to the fixture by threading the connection portion 190b of the base 182b into the receptacle 150. The user then positions the extension 186b relative to the base 182b. Specifically, the user slides the extension 186b along the base 182b, causing the arms 214b, 218b to slide along and cover the key 246b. The extension 186b may be coupled to the base 182b in a retracted position (FIG. 8A), in which the first end 181b of the base 182b abuts an end 248b of the key 246b, a fully extended position (FIG. 8B), in which the first end 181b of the base 182b is positioned adjacent the second end 187b of the extension 186b, or a plurality of partially extended positioned between the retracted position and the fully extended position. In order to couple the extension 186b to the base 182b in a given position, the user secures the clamp around the extension 186b and the base 182b. In the retracted position, the slots 166b on the base 182b are aligned with the slots 226b of the arms 214b, 218b. The user then positions fasteners (e.g., pins) through the slots 166b, 226b. The fasteners may then protrude through corresponding apertures on the plumbing fixture during use, securing the arm 46b to the plumbing fixture.

In some embodiments (FIGS. 9A-9B), the arm may alternatively include a rectangular cross-section. In such embodiments, the base 182b and the extension 186b each include a rectangular cross-section.

In further embodiments (FIGS. 10A-10B), the key 246b includes grooves 254b positioned along sides of the key 246b. Specifically, the key 246b includes two grooves 254b oriented parallel to each other on opposite sides of the key 246b. The arms 214b, 218b include corresponding rails 258b configured to engage the grooves 254b. Specifically, each of the arms 214b, 218b include a single rail 258b extending along an inner surface 262b of the arms 214b, 218b. In such embodiments, the arms 214b, 218b extend from side surfaces 266b of the solid portion 210b of the extension 186b. Each of the arms 214b, 218b additionally include a circular aperture 270b extending through the extension 186b. The circular apertures 186b are shaped and sized to receive a fastener. Alternatively, in some embodiments (FIGS. 11A-11B), the rails 258b are positioned on sides of the key 246b and the corresponding grooves 254b are positioned on the inner surfaces 262b of the arms 214b, 218b.

During positioning of the arm 46b, the user slides the extension 186b along the base 182b, causing the arms 214b, 218b to slide along and cover the key 246b. Specifically, the rails 258b of the arms 214b, 218b slide along the grooves 254b of the key 246b. In order to couple the extension 186b to the base 182b in a given position, the user positions fasteners (e.g., pins) through the circular apertures 270b on the arms 214b, 218b. The fasteners abut against the grooves

254b of the key 246b, providing a clamping force against the key 246b and securing the extension 186b to the base 182b.

FIGS. 12A-13B illustrate another embodiment of an arm 46c, with like components designated with a "c." The arm 46c is largely identical to the arms 46, 50, with some differences, as described below.

With reference to FIG. 12A-12B, the arm 46c is cylindrical in cross-section. The arm 46b includes a stationary base 182c and an extension 186c, which is movable relative to the base 182c. The base 182c includes a first end 181c, and a second end 183c opposite the first end 181c. The first end 181c extends outward from the frame 14 and the second end 183c of the base 182c is secured to the receptacle 150 of the plate 66, 70. The second end 183c of the base 182c includes a connection portion 190c having threads 194c corresponding to the threads positioned on the inner surface of the receptacle 150. Therefore, the connection portion 190c of the arm 46c is threadably coupled to the receptacle 150. In alternative embodiments, the arm 46c may be threaded along the length of partial length of the base 182c. In alternative embodiments, the arm 46c may be secured to the receptacle 150 via fasteners.

The first end 181c of the base 182c includes a keyed portion 246c having grooves 254c extending into the base 182c. Specifically, the keyed portion 246c includes four grooves 254c. The grooves 254c are equidistantly spaced around the base 182c and form four, equidistantly spaced rails 274c. An aperture 278c extends through the keyed portion 246c. Specifically, the aperture 278c extends through two of the rails 274c and is shaped and sized to receive a fastener.

The base 182c includes elongated slots 166c, 250c, or apertures, extending through the base 182c. In the illustrated embodiments, the base 182c includes one elongate slot 250c extending along the keyed portion 246c, and two elongate slots 166c extending between the keyed portion 246c and the connection portion 190c of the arm 46c. In alternative embodiments, the slots 166c, 250c may include additional shapes or sizes, and/or extend along a shorter or longer portion of the base 182c. Additionally, in alternative embodiments, the base 182c may include fewer or more slots.

The extension 186c includes a first end 185c, and a second end 187c opposite the first end 185c. The extension 186c is cylindrical and includes a cut-out 206c extending from the second end 187c of the extension 186c through a portion of the extension 186c. The cut-out 206c forms a solid cylindrical portion 282c, and a hollow cylindrical portion 286c. The solid cylindrical portion 282c includes an elongate slot 290c, or aperture, extending through the extension 186c. In the illustrated embodiments, the solid cylindrical portion 282c includes one slot 290c. However, in alternative embodiments, the solid cylindrical portion 282c may include fewer or more slots. An opening (not shown) extends through a portion of the hollow cylindrical portion 286c, forming a non-continuous wall (not shown). An internal surface (not shown) of the hollow cylindrical portion 286c includes grooves (not shown) extending into the extension 186c. The grooves are shaped and sized to receive the corresponding rails 274c positioned on the keyed portion 246c of the base 182c. The hollow cylindrical portion 286c includes a first elongate slot 294c and a second elongate slot 296c extending through the extension 186c. The first elongate slot 294c extends along an axis parallel to and collinear with an axis of the elongate slot 290c of the solid cylindrical portion 282c, and the second elongate slot 296c extends along an axis parallel to and offset from the axis of the

11

elongate slot 290c of the solid cylindrical portion 282c. The hollow cylindrical portion 286c additionally includes cylindrical apertures 298 extending through the extension 186c. In the illustrated embodiments, the hollow cylindrical portion 286c includes two elongate slots 294c, 296c and two cylindrical apertures 298c. However, in alternative embodiments, the hollow cylindrical portion 286c may include fewer or more slots and/or apertures. The slots 294c, 296c extend through two of the grooves formed on the inner surface of the hollow cylindrical portion 286c.

The arm 46c may additionally or alternatively include a sleeve, or collar, (not shown) supported by the arm 46c movable (e.g., slidably) along the arm 46c. The sleeve includes an outer surface configured to be engaged by the user to move the sleeve relative to the arm 46c. Specifically, the sleeve may be two washers secured together via a fastener (e.g., a bolt, etc.). The sleeve clamps around the arm 46c in order to secure the extension 186c to the base 182c in a given position. In some embodiments, the sleeve includes apertures extending through the sleeve. The sleeve apertures, the slots 166c, 250c on the base 182c, and the slots 290c, 294c, 296c on the extension 186c are shaped and sized to fasteners (e.g., pins).

In order to position the arm 46c during operation, the user secures the arm 46c to the fixture by threading the connection portion 190c of the base 182c into the receptacle 150. The user then positions the extension 186c relative to the base 182c. Specifically, the user slides the extension 186c along the base 182c, causing the grooves of the hollow cylindrical portion 286c to slide along and cover the rails 274c of the keyed portion 246c. The extension 186c may be coupled to the base 182c in a retracted position (FIG. 12A), in which the first end 181c of the base 182c abuts an end 248c of the keyed portion 246c, a fully extended position, in which the first end 181c of the base 182c is positioned adjacent the second end 187c of the extension 186c, or a plurality of partially extended positions (FIG. 12B) between the retracted position and the fully extended position. In order to couple the extension 186c to the base 182c in a given position, the user secures the clamp around the extension 186c and the base 182c. The user may insert fasteners into the apertures 298c of the hollow cylindrical portion 286c. The fasteners abut against the grooves of the keyed portion 246c, providing a clamping force against the keyed portion 246c and securing the extension 186c to the base 182c. Additionally, when the extension 186c is in the retracted position, or one of the partially extended positions, the aperture 278c of the keyed portion 274c aligns with the elongate slots 296c of the hollow cylindrical portion 286c. The user may insert fasteners through the slots 296c and into the apertures 278c of the keyed portion 274c, thereby securing the extension 186c to the base 182c.

In order to secure the arm 46 to the plumbing fixture, the user inserts fasteners (e.g., pins) through the elongate slots 166c of the base 182c and the elongate slot 290c of the solid cylindrical portion 282c of the extension 186c. The fasteners then protrude through corresponding apertures on the plumbing fixture during use, securing the arm 46c to the plumbing fixture.

In some embodiments (FIGS. 13A-13B), the arm 46c includes flats 302c, 306c extending along the length of the arm 46c. Specifically, the arm 46c includes a first flat 302c and a second flat 306c. The flats 302c, 306c are positioned on opposite sides of the arm 46c and extend parallel to each other. The second elongate slot 296c of the hollow cylindrical portion 286c is positioned on the first flat 302c. In

12

alternative embodiments, the arm 46c may include fewer or additional flats extending along the arm.

FIGS. 14A-14B illustrate another embodiment of an arm 46d, with like components designated with a "d." The arm 46d is largely identical to the arms 46, 50, with some differences, as described below.

With reference to FIGS. 14A-14B, the arm 46d is cylindrical in cross-section. The arm 46d includes a stationary base 182d and an extension 186d, which is movable relative to the base 182d. The base 182d includes a first end, and a second end 183d opposite the first end. The first end extends outward from the frame 14 and includes a first connection portion 310d. The second end 183d of the base 182d includes a second connection portion 314d secured to the receptacle 150 of the plate 66, 70. The second connection portion 314d includes threads 194d corresponding to the threads positioned on the inner surface of the receptacle 150. Therefore, the second connection portion 314d of the arm 46d is threadably coupled to the receptacle 150. The first connection portion 310d includes threads 318d that are finer (e.g., include a smaller pitch) than the threads 194d of the second connection portion 314d. In alternative embodiments, the arm 46d may be threaded along the length base 182d, or along a partial length of the base 182d. In alternative embodiments, the arm 46d may be secured to the receptacle 150 via fasteners.

The base 182d includes one or more elongated slots 166d, 322d, or apertures, extending through the base 182d. In other constructions, the elongated slot(s) 166d are recessed within the base 182d and do not extend completely through the base 182d. In the illustrated embodiments, the base 182d includes one elongate slot 322d extending along the first connection portion 310d, and two elongate slots 166d extending between the first connection portion 310d and the second connection portion 314d. The first connection portion 310d additionally includes a cylindrical aperture 323d extending through the base 182d. Ends of the aperture 323d are shaped and sized to receive screws 326d. As will be explained in greater detail below, the screw 326d serves as an indicator. More specifically, the screw 326d indicates to the user a position in which the extension 186d needs to be secured to the base 182d in order to align with a plumbing fixture. In alternative embodiments, the apertures may receive different fasteners. In other alternative embodiments, the slots 166d, 322d and/or aperture 323d may include additional shapes or sizes, and/or extend along a shorter or longer portion of the base 182d. Additionally, in alternative embodiments, the base 182d may include fewer or more slots and/or apertures.

The extension 186d includes a first end 185d, and a second end 187d opposite the first end 185d. The extension 186d is cylindrical and includes a bore, or opening, 325d extending from the second end 187d of the extension 186d through a portion of the extension 186d. The extension 186d includes a solid portion 282d, and a hollow portion 286d. The solid portion 282d includes an elongate slot 290d, or aperture, extending through the extension 186d. In the illustrated embodiments, the solid portion 282d includes one slot 290d. However, in alternative embodiments, the solid portion 282d may include fewer or more slots.

An internal surface of the hollow portion 286d includes threads corresponding to the threads on the first connection portion 310d of the base 182d. As previously mentioned, the threads 318d on the first connection portion 310d are finer than the threads 194d on the second connection portion 314d. The finer threads allow for finer adjustment of the extension 186d relative to the base 182d. The hollow portion 286d includes a first elongate slot 294d and a second

elongate slot 296d extending through the extension 186d. The first elongate slot 294d extends along an axis parallel to and collinear with an axis of the elongate slot 290d of the solid portion 282d, and the second elongate slot 296d extends along an axis parallel to and offset from the axis of the elongate slot 290d of the solid cylindrical portion 282d.

In order to position the arm 46d during operation, the user secures the arm 46d to the fixture by threading the second connection portion 314d of the base 182d into the receptacle 150. The user then positions (e.g., threads) a lock nut (or like fastener) onto the first connection portion 310d, and then positions the extension 186d relative to the base 182d. Specifically, the user threads the second end 187d of the extension 186d onto the first connection portion 310d of the base 182d. As the extension 186d is threaded onto the base 182d, the lock nut rotates with the extension 186d, increasing the stability of the arm 46d. The extension 186d may be threadably coupled to the base 182d in a retracted position (FIG. 14A), in which the base 182d is retracted into the extension 186d, a fully extended position, in which the extension 186d extends away from the base 182d, or a plurality of partially extended positions (FIG. 14B) between the retracted position and the fully extended position. More specifically, in the retracted position, the first end of the base 182d abuts an end of the solid cylindrical portion 282d, and in the fully extended position, the first end of the base 182d is positioned adjacent the second end 187d of the extension 186d.

When the extension 186d is in the retracted position, or one of the partially extended positions, the cylindrical aperture of the first connection portion 310d aligns with the second elongate slot 296d of the hollow cylindrical portion 286d. The user inserts the screws 326d through the second slot 296d and into the cylindrical aperture of the first connection portion 310d, thereby securing the extension 186d to the base 182d. The screws 326d indicate where the extension 186d needs to be positioned relative to the arm 46d in order to align with the plumbing fixture. When the screws 326d are fully inserted into the second slot 296d and the aperture, the extension 186d is prevented from rotating relative to the base 182d.

In order to secure the arm 46d to the plumbing fixture, the user inserts fasteners (e.g., pins) through the elongate slots 166d, 322d of the base 182d, the first elongate slot 294d of the hollow cylindrical portion 286, and the slot 290d of the solid cylindrical portion 282d. The fasteners then protrude through corresponding apertures on the plumbing fixture during use, securing the arm 46d to the plumbing fixture.

FIGS. 15A-19B illustrate another embodiment of an arm 46e, with like components designated with an “e.” The arm 46e is largely identical to the arms 46, 50, with some differences, as described below.

With reference to FIGS. 15A-15B, the arm 46e is cylindrical in cross-section. The arm 46e includes a stationary base 182e, a first extension 330e, which is movable relative to the base 182e, and a second extension 334e, which is movable relative to the first extension 330e. The base 182e includes a first end 181e, and a second end 183e opposite the first end 181e. The first end 181e extends outward from the frame 14 and the second end 183e of the base 182e is secured to the receptacle 150 of the plate 66, 70. The second end 183e of the base 182e includes a connection portion 190e having threads 194e corresponding to the threads positioned on the inner surface of the receptacle 150. Therefore, the connection portion 190e of the arm 46e is threadably coupled to the receptacle 150. In alternative embodiments, the arm 46e may be threaded along the length of

partial length of the base 182e. In alternative embodiments, the arm 46e may be secured to the receptacle 150 via fasteners.

A portion of the base 182e extending from the first end 181e of the base 182 to a first end 189e of the connection portion 190e is hollow and includes a channel (not shown). An elongate slot 166e, or aperture, extends through the base 182e and extends between the first end 181e of the base 182e and the first end 189e of the connection portion 190e. In alternative embodiments, the slot 166e may include additional shapes or sizes, and/or extend along a shorter or longer portion of the base. In some constructions, the elongate slot 166e is recessed within the base 182e and does not extend completely through the base 182e. Additionally, in alternative embodiments, the base 182e may include additional slots.

The first extension 330e includes a first end 329e, and a second end 331e opposite the first end 329e. The first extension 330e is cylindrical in cross-section and includes a main portion 338e and a reduced diameter portion 342e. The main portion 338e is hollow and includes an elongate slot 346e, or aperture, extending through the first extension 330e. The elongate slot 346e extends along the length of the main portion 338e, from the first end 329e of the first extension 330e to the reduced diameter portion 342e. The reduced diameter portion 342e is solid and includes a diameter smaller than a diameter of the main portion 338e. Specifically, the reduced diameter portion 342e is sized to be received within the channel of the base 182e. The reduced diameter portion 342e includes an elongate slot 350e, or aperture, extending through the first extension 330e. The elongate slot 350e extends along the length of the reduced diameter portion 350e, from the second end 331e of the first extension 330e to the main portion 338e. In alternative embodiments, the slots 346e, 350e of the first extension 330e may include additional shapes or sizes, and/or extend along a shorter or longer portion of the first extension 330e. Additionally, in alternative embodiments, the first extension 330e may include fewer or more slots.

The second extension 334e includes a first end 333e, and a second end 335e opposite the first end 333e. The second extension 334e is cylindrical in cross-section and includes a main portion 354e and a reduced diameter portion 358e. The main portion 358e is solid and includes an elongate slot 362e, or aperture, extending through the second extension 334e. The elongate slot 362e extends along the length of the main portion 354e, from the first end 333e of the second extension 334e to the reduced diameter portion 358e. The reduced diameter portion 358e is solid and includes a diameter smaller than a diameter of the main portion 354e. Specifically, the reduced diameter portion 358e is sized to be received within the hollow, main portion 338e of the first extension 330e. The reduced diameter portion 358e includes an elongate slot 366e, or aperture, extending through the second extension 334e. The elongate slot 366e extends along the length of the reduced diameter portion 358e, from the second end 335e of the second extension 334e to the main portion 354e. In alternative embodiments, the slots 362e, 366e of the second extension 334e may include additional shapes or sizes, and/or extend along a shorter or longer portion of the second extension 334e. Additionally, in alternative embodiments, the second extension 334e may include fewer or more slots. In the illustrated embodiments, the second extension 334e is identical in size to the first extension 330e. Additionally, the hollow, cylindrical portion of the base, the main portion 338e of the first extension 330e, the reduced diameter portion 342e of the first extension

330e, the main portion 354e of the second extension 334e, and the reduced diameter portion 358e of the second extension 334e have the same length. However, in alternative embodiments, the components may include different lengths.

The arm 46e may additionally or alternatively include a sleeve, or collar, (not shown) supported by the arm 46e movable (e.g., slidable) along the arm 46e. The sleeve includes an outer surface engageable by the user to move the sleeve relative to the arm 46e. Specifically, the sleeve may be two washers secured together via a fastener (e.g., a bolt, etc.). The sleeve clamps around the arm 46e in order to secure the first extension 330e and the second extension 334e to the base 182e in a given position. In some embodiments, the sleeve includes apertures extending through the sleeve. The apertures, the slots 166e on the base 182e, and the slots 346e, 350e, 362e, 366e on the extensions 330e, 334e are shaped and sized to fasteners (e.g., pins). In the illustrated embodiments, the arm 46e includes a first sleeve to secure the first extension 330e to the base 182e in a given position, and a second sleeve to secure the second extension 334e to the first extension 330e in a given position.

In order to position the arm 46e during operation, the user secures the arm 46e to the fixture by threading the connection portion 190e of the base 182e into the receptacle 150. The user then positions the extensions 330e, 334e relative to the base 182e. Specifically, the user slides the first extension 330e relative to the base 182e and the second extension 334e relative to the first extension 330e, causing the reduced diameter portion 342e of the first extension 330e to telescope in and out of the hollow cylindrical portion of the base 182e, and the reduced diameter portion 358e of the second extension 334e to telescope in and out of the main portion 338e of the first extension 330e. The extensions 330e, 334e may be coupled to the base 182e in a retracted position (FIG. 15A), a partially extended position, or a fully extended position (FIG. 15B). In the retracted position, the reduced diameter portion 342e of the first extension 330e is seated within the hollow cylindrical portion of the base 182e and the reduced diameter portion 358e of the second extension 334e is seated within the main portion 338e of the first extension 330e. In the partially extended position, the reduced diameter portion 342e of the first extension 330e is seated within the hollow cylindrical portion of the base 182e and the reduced diameter portion 358e of the second extension 334e is extended out of the main portion 338e of the first extension 330e. In the fully extended position, the reduced diameter portion 342e of the first extension 330e is extended out of the hollow cylindrical portion of the base 182e and the reduced diameter portion 358e of the second extension 334e is extended out of the main portion 338e of the first extension 330e. The extensions 330e, 334e may additionally be coupled to the base 182e in a plurality of positions between the retracted position and the partially extended position, and a plurality of positions between the partially extended position and the fully extended position.

In order to couple the extensions 330e, 334e to the base 182e in a given position, the user secures the first clamp around the first extension 330e and the base 182e, and the second clamp around the first extension 330e and the second extension 334e. The user then positions fasteners (e.g., pins) through the slots 166e, 346e, 350e, 362e, 366e. The fasteners may then protrude through corresponding apertures on the plumbing fixture during use, securing the arm 46e to the plumbing fixture.

In some embodiments (FIGS. 16A-16B), the reduced diameter portions 342e, 358e of the first and second exten-

sion 330e, 334e are keyed. More specifically, the reduced diameter portions 342e, 358e include four rails 370e extending parallel to each other, and extending from the second end 331e, 335e of the extensions 330e, 334e to the main portions 338e, 354e of the extensions 330e, 334e. In such instances, an inner surface (not shown) of the hollow cylindrical portion of the base 182e and an inner surface (not shown) of the main body 338e of the first extension 330e are keyed. Specifically, the inner surfaces include grooves 374e forming a shape corresponding to the shape of the reduced diameter portions 342e, 358e.

During positioning of the arm 46e, the user telescopes the reduced diameter portion 342e of the first extension 330e into and out of the hollow cylindrical portion of the base 182e, and the reduced diameter portion 358e of the second extension 334e into and out of the main portion 338e of the first extension 330e, causing the rails 370e of the extensions 330e, 334e to slide along the corresponding grooves 374e. The rails 370e and grooves 374e prevent rotation of the first and second extensions 330e, 334e relative to the base 182e.

In some embodiments (FIGS. 17A-17B), the reduced diameter portions 342e, 358e of the first and second extension 330e, 334e include a rectangular cross-section. In such instances, the inner surface of the hollow cylindrical portion of the base 182e and the inner surface of the main portion 338e of the first extension 330e have a corresponding, rectangular shape.

In some embodiments (FIGS. 18A-18B), the entire arm 46e includes a rectangular cross-section. In such instances, an outer surface of the hollow cylindrical portion of the base 182e, the main portion 338e and the reduced diameter portion 342e of the first extension 330e, and the main portion 354e and the reduced diameter portion 358e of the second extension 334e are rectangular. Additionally, the inner surfaces of the hollow cylindrical portion of the base 182e and the main portion 338e of the first extension 330e are rectangular. The rectangular shape prevents rotation of the first and second extensions 330e, 334e relative to the base 182e during operation.

In some embodiments (FIGS. 19A-19B), the outer surface of the hollow cylindrical portion of the base 182e includes a larger, thicker diameter than the outer surface of the first and second extensions 330e, 334e. In such instances, the thicker diameter of the hollow cylindrical portion increases the durability of the base 182e. Therefore, when the arm 46e is positioned against the plumbing fixture, the arm 46e is capable of withstanding greater stress.

FIGS. 20A-21B illustrate another embodiment of an arm 46f, with like components designated with an "f". The arm 46f is largely identical to the arms 46, 50, with some differences, as described below.

With reference to FIGS. 20A-20B, the arm 46f is cylindrical in cross-section. The arm 46f includes a stationary base 182f, a first extension 330f, which is movable relative to the base 182f, and a second extension 334f, which is movable relative to the first extension 330f. The base 182f includes a first end 181f, and a second end 183f opposite the first end 181f. The first end 181f extends outward from the frame 14 and the second end 183f of the base 182f is secured to the receptacle 150 of the plate 66, 70. The second end 183f of the base 182f includes a connection portion 190f having threads 194f corresponding to the threads positioned on the inner surface of the receptacle 150. Therefore, the connection portion 190f of the arm 46f is threadably coupled to the receptacle 150. In alternative embodiments, the arm 46f may be threaded along the length of partial length of the base

182f. In alternative embodiments, the arm 46f may be secured to the receptacle 150 via fasteners.

The base 182f includes a reduced diameter portion 378f extending from the first end 181f of the base 182f to the connection portion 190f. The reduced diameter portion 378f is solid and includes a rectangular cross-section. However, in some embodiments, the reduced diameter portion 378f may include a cross-section of alternative shapes. The reduced diameter portion 378f includes a diameter smaller than a diameter of the connection portion 190f. An elongate slot 166f, or aperture, extending through the base 182f between the first end 181f of the base 182f and the connection portion 190f. In alternative embodiments, the slot 166f may include additional shapes or sizes, and/or extend along a shorter or longer portion of the base 182f. In some constructions, the elongate slot 166f is recessed within the base 182f and does not extend completely through the base 182f. Additionally, in alternative embodiments, the base 182f may include additional slots.

The first extension 330f includes a first end 329f, and a second end 331f opposite the first end 329f. The first extension 330f includes a cylindrical main portion 338f and a rectangular reduced diameter portion 342f. The main portion 338f is hollow and includes an inner surface having a rectangular shape. Specifically, the inner surface forms a chamber shaped and sized to receive the reduced diameter portion 378f of the base 182f. The main portion 338f additionally includes a first elongate slot 382f, or aperture, extending through the first extension 330f, and a second elongate slot 386f, or aperture, extending partially through the main portion 338f and into the chamber. The elongate slots 382f, 386f extend along the length of the main portion 338f, from the second end 331f of the first extension 330f to the reduced diameter portion 342f. The reduced diameter portion 342f is solid and includes a diameter smaller than a diameter of the main portion 338f. The reduced diameter portion 342f includes an elongate slot 350f, or aperture, extending through the first extension 330f. The elongate slot 350f extends along the length of the reduced diameter portion 342f, from the first end 329f of the first extension 330f to the main portion 338f. In alternative embodiments, the slots 350f, 382f, 386f of the first extension 330f may include additional shapes or sizes, and/or extend along a shorter or longer portion of the first extension 330f. Additionally, in alternative embodiments, the first extension 330f may include fewer or more slots.

The second extension 334f includes a first end 333f, and a second end 335f opposite the first end 333f. The second extension 334f is cylindrical and includes an opening extending from the second end 335f of the extension 334f through a portion of the extension 334f. The opening forms a solid cylindrical portion 282f, and a hollow cylindrical portion 286f. The solid cylindrical portion 282f includes an elongate slot 290f, or aperture, extending through the extension 334f. In the illustrated embodiments, the solid portion 282f includes one slot 290f. However, in alternative embodiments, the solid portion 282f may include fewer or more slots. The hollow cylindrical portion 286f includes an inner surface having a rectangular shape. Specifically, the inner surface forms a chamber shaped and sized to receive the reduced diameter portion 342f of the first extension 330f. The hollow cylindrical portion 286f additionally includes a first elongate slot 390f, or aperture, extending through the second extension 334f, and a second elongate slot 394f, or aperture, extending partially through the hollow cylindrical portion 286f and into the chamber. The elongate slots 390f, 394f extend along the length of the hollow cylindrical

portion 286f, from the second end 335f of the second extension 334f to the solid cylindrical portion 282f.

The arm 46f may additionally or alternatively include a sleeve, or collar, (not shown) supported by the arm 46f movable (e.g., slidable) along the arm 46f. The sleeve includes an outer surface engageable by the user to move the sleeve relative to the arm 46f. Specifically, the sleeve may be two washers secured together via a fastener (e.g., a bolt, etc.). The sleeve clamps around the arm 46f in order to secure the first extension 330f and the second extension 334f to the base 182f in a given position. In some embodiments, the sleeve includes apertures extending through the sleeve. The apertures, the slot 166f on the base 182f, and the slots 290f, 382f, 386f, 390f, 394f on the extensions 330f, 334f are shaped and sized to fasteners (e.g., pins). In the illustrated embodiments, the arm 46f includes a first sleeve to secure the first extension 330f to the base 182f in a given position, and a second sleeve to secure the second extension 334f to the first extension 330f in a given position.

In order to position the arm 46f during operation, the user secures the arm 46f to the fixture by threading the connection portion 190f of the base 182f into the receptacle 150. The user then positions the extensions 330f, 334f relative to the base. Specifically, the user slides the first extension 330f relative to the base 182f and the second extension 334f relative to the first extension 330f, causing the main portion 338f of the first extension 330f to telescope over the reduced diameter portion 378f of the base 182f, and the hollow cylindrical portion 286f of the second extension 334f to telescope over the reduced diameter portion 342f of the first extension 330f. The extensions 330f, 334f may be coupled to the base 182f in a retracted position (FIG. 20A), a partially extended position, or a fully extended position (FIG. 20B). In the retracted position, the reduced diameter portion 378f of the base 182f is seated within the main portion 338f of the first extension 330f and the reduced diameter portion 342f of the first extension 330f is seated within the hollow cylindrical portion 286f of the second extension 334f. In the partially extended position, the reduced diameter portion 378f of the base 182f is seated within the main portion 338f of the first extension 330f and the reduced diameter portion 342f of the first extension 330f is extended out of the hollow cylindrical portion 286f of the second extension 334f. In the fully extended position, the reduced diameter portion 378f of the base 182f is extended out of the main portion 338f of the first extension 330f and the reduced diameter portion 342f of the first extension 330f is extended out of the hollow cylindrical portion 286f of the second extension 334f. The extensions 330f, 334f may additionally be coupled to the base 182f in a plurality of positions between the retracted position and the partially extended position, and a plurality of positions between the partially extended position and the fully extended position.

In order to couple the extensions 330f, 334f to the base 182f in a given position, the user secures the first clamp around the first extension 330f and the base 182f, and the second clamp around the first extension 330f and the second extension 334f. The user then positions fasteners (e.g., pins) through the slots. The fasteners may then protrude through corresponding apertures on the plumbing fixture during use, securing the arm 46f to the plumbing fixture.

In some embodiments (FIGS. 21A-21B), the reduced diameter portion 378f of the base 182f and the reduced diameter portion 342f of the first extension 330f are keyed. More specifically, the reduced diameter portions 342f, 378f include four rails 370f extending parallel to each other, and extending along the reduced diameter portions 342f, 378f. In

such instances, the inner surface of the main portion 338f of the first extension 330f and the inner surface of the hollow cylindrical portion 286f of the second extension 334f are keyed. Specifically, the inner surfaces include grooves 374f, therefore the chamber includes a shape corresponding to the shape of the reduced diameter portions 342f, 378f.

During positioning of the arm 46f, the user telescopes the main portion 338f of the first extension 330f over the reduced diameter portion 378f of the base 182f, and the hollow cylindrical portion 286f of the second extension 334f over the reduced diameter portion 342f of the first extension 330f, causing the rails 370f of the reduced diameter portions 342f, 378f to slide along the corresponding grooves 374f. The rails 370f and grooves 374f prevent rotation of the first and second extensions 330f, 334f relative to the base 182f.

FIGS. 22A-22B illustrate another embodiment of an arm 46g, with like components designated with a "g." The arm 46g is largely identical to the arms 46, 50, with some differences, as described below.

With reference to FIGS. 22A-22B, the arm 46g is cylindrical in cross-section. The arm 46g includes a stationary base 182g, a first extension 330g, which is movable relative to the base 182g, and a second extension 334g, which is movable relative to the first extension 330g. The base 182g includes a first end 181g, and a second end 183g opposite the first end 181g. The first end 181g extends outward from the frame 14 and the second end 183g of the base 182g is secured to the receptacle 150 of the plate 66, 70. The second end 183g of the base 182g includes a connection portion 190g having threads 194g corresponding to the threads positioned on the inner surface of the receptacle 150. Therefore, the connection portion 190g of the arm 46g is threadably coupled to the receptacle 150. In alternative embodiments, the arm 46g may be threaded along the length of partial length of the base 182g. In alternative embodiments, the arm 46g may be secured to the receptacle 150 via fasteners.

The base 182g includes a main body 398g extending from the first end 181f of the base 182f to the connection portion 190f. The main body 398g is solid and includes a circular cross-section. However, in some embodiments, the main body 398g may include a cross-section of alternative shapes. The main body 398g includes rails 402g extending from the main body 398g. Specifically, the main body 398g includes four rails 402g extending parallel to each other and equidistantly spaced around the body 398g. An elongate slot 166g, or aperture, extends through the base 182g between the first end 181g of the base 182g and the connection portion 190g. In alternative embodiments, the slot 166g may include additional shapes or sizes, and/or extend along a shorter or longer portion of the base 182g. In some constructions, the elongate slot 166g is recessed within the base 182g and does not extend completely through the base 182g. Additionally, in alternative embodiments, the base 182g may include additional slots.

The first extension 330g includes a first end 329g, and a second end 331g opposite the first end 329g. The first extension 330g is cylindrical and includes a cut-out extending from the second end 187g of the extension 186g through a portion of the extension 186g. The cut-out forms a solid cylindrical portion 282g, and a hollow cylindrical portion 286g. The solid cylindrical portion 282g includes elongate channels 198g, 202g extending into sides of the first extension 330g. Specifically, the solid cylindrical portion 282g includes a first channel 198g and a second channel 202g extending parallel to each other and positioned on opposite sides of the first extension 330g. The solid cylindrical

portion 282g includes an elongate slot 290g, or aperture, extending through the first extension 330g. In the illustrated embodiments, the solid cylindrical portion 282g includes one slot 290g. However, in alternative embodiments, the solid cylindrical portion 282g may include fewer or more slots. The hollow cylindrical portion 286g includes cut-outs 406g extending into the first extension 330g. The cut-outs 406g are shaped and sized to receive the corresponding rails 402g positioned on the main body 398g of the base 182g. The hollow cylindrical portion 286g includes an elongate slot 294g extending through the first extension 330g. The elongate slot 294g extends along an axis parallel to and collinear with an axis of the elongate slot 290g of the solid cylindrical portion 282g. In the illustrated embodiments, the first extension includes two elongate slots 290g, 294g. However, in alternative embodiments, the first extension may include fewer or more slots and/or apertures.

The second extension 334g includes a first end 333g, and a second end 335g opposite the first end 333g. The second extension 334g is cylindrical and includes a cut-out 206g extending from the second end 335g of the second extension 334g through a portion of the second extension 334g. The cut-out 206g forms a solid portion 210g, a first elongate arm 214g, and a second elongate arm 218g. The elongate arms 214g, 218g extend from the solid portion 210g. The solid portion 210g includes an elongate slot 222g, or aperture, extending through the extension 334g. In the illustrated embodiments the solid portion 210g includes one slot 222g. However, in alternative embodiments, the solid portion 210g may include fewer or more slots. The arms 214g, 218g extend from the solid portion 210g and are oriented parallel to each other and on opposite sides of the extension 334g. The arms 214g, 218g are shaped and sized to be received within the first channel 198g and the second channel 202g of the first extension 330g.

The arm 46g may additionally or alternatively include a sleeve, or collar, (not shown) supported by the arm 46g movable (e.g., slidably) along the arm 46g. The sleeve includes an outer surface engageable by the user to move the sleeve relative to the arm 46g. Specifically, the sleeve may be two washers secured together via a fastener (e.g., a bolt, etc.). The sleeve clamps around the arm 46g in order to secure the first extension 330g and the second extension 334g to the base 182g in a given position. In some embodiments, the sleeve includes apertures extending through the sleeve. The apertures, the slot 166g on the base 182g, and the slots 222g, 290g, 294g on the extensions 330g, 334g are shaped and sized to fasteners (e.g., pins). In the illustrated embodiments, the arm 46g includes a first sleeve to secure the first extension 330g to the base 182g in a given position, and a second sleeve to secure the second extension 334g to the first extension 330g in a given position.

In order to position the arm 46g during operation, the user secures the arm 46g to the fixture by threading the connection portion 190g of the base 182g into the receptacle 150. The user then positions the extensions 330g, 334g relative to the base 182g. Specifically, the user slides the first extension 330g relative to the base 182g and the second extension 334g relative to the first extension 330g, causing the hollow cylindrical portion 286g of the first extension 330g to telescope over the main body 398g of the base 182g, and the arms 214g, 218g of the second extension 334g to slide along the channels 198g, 202g of the first extension 330g. The extensions 330g, 334g may be coupled to the base 182g in a retracted position (FIG. 22A), a partially extended position, or a fully extended position (FIG. 22B). In the retracted position, the main body of the base 182g is seated within the

21

hollow cylindrical portion **286g** of the first extension **330g** and the arms **214g**, **218g** of the second extension **330g** are seated within the channels **198g**, **202g** of the first extension **330g**. In the partially extended position, the main body **398g** of the base **182g** is seated within the hollow cylindrical portion **286g** of the first extension **330g** and the arms **214g**, **218g** of the second extension **334g** are extended out of the channels **198g**, **202g** of the first extension **330g**. In the fully extended position, the main body **398g** of the base **182g** is extended out of the hollow cylindrical portion **286g** of the first extension **330g** and the arms **214g**, **218g** of the second extension **334g** are extended out of the channels **198g**, **202g** of the first extension **330g**. The extensions **330g**, **334g** may additionally be coupled to the base **182g** in a plurality of positions between the retracted position and the partially extended position, and a plurality of positions between the partially extended position and the fully extended position.

In order to couple the extensions **330g**, **334g** to the base **182g** in a given position, the user secures the first clamp around the first extension **330g** and the base **182g**, and the second clamp around the first extension **330g** and the second extension **334g**. The user then positions fasteners (e.g., pins) through the slots. The fasteners may then protrude through corresponding apertures on the plumbing fixture during use, securing the arm **46g** to the plumbing fixture.

Various features and advantages are set forth in the following claims.

What is claimed is:

1. A fixture carrier for supporting a plumbing fixture, the fixture carrier comprising:
an upright; and
an arm coupled to the upright and configured to support the plumbing fixture, the arm including a base, and
an extension configured to move relative to the base, wherein the arm is configurable in a first position where at least a portion of the base is retracted into the extension, a second position where the extension is extended away from the base, and a plurality of positions between the first position and the second position, and
wherein the base includes an aperture and the extension includes an elongate slot, and wherein when the arm is in the second position the aperture is aligned with the elongate slot.

22

2. The fixture carrier of claim 1, wherein the upright defines a first axis, and the arm defines a second axis oriented perpendicular to the first axis, wherein the extension telescopes relative to the base about the second axis.

5 3. The fixture carrier of claim 1, further comprising a coupling mechanism configured to couple the arm to the upright.

10 4. The fixture carrier of claim 3, wherein the coupling mechanism includes a bracket coupled to the upright, and a plate positioned between the bracket and the arm, wherein the plate is coupled to the arm and movable relative to the bracket.

15 5. The fixture carrier of claim 4, wherein the plate includes a receptacle, wherein the base is threadably coupled to the receptacle.

6. The fixture carrier of claim 1, wherein the aperture and the elongate slot are configured to receive a fastener.

7. A fixture carrier for supporting a plumbing fixture, the fixture carrier comprising:
20 an upright; and

an arm coupled to the upright and configured to support the plumbing fixture, the arm including a first portion coupled to the upright, and a second portion coupled to the first portion and including a bore, wherein the first portion is configured to be threadably received within the bore,

wherein the arm is configurable in a first position where at least a portion of the first portion is retracted into the second portion, a second position wherein the first portion is extended away from the second portion, and a plurality of positions between the first position and the second position, and

wherein the first portion includes an aperture, wherein the second portion includes an elongate slot, and wherein when the arm is in the second position the aperture is aligned with the elongate slot.

35 8. The fixture carrier of claim 7, wherein a first end of the first portion includes first threads, and a second end of the first portion includes second threads.

40 9. The fixture carrier of claim 8, wherein the second threads include a greater pitch than the first threads.

10. The fixture carrier of claim 7, wherein the first portion is threadably coupled to the upright.
